UNITED STATES PATENT OFFICE.

JESSE M. LILLPOP, OF KYANA, INDIANA, ASSIGNOR OF ONE-HALF TO
JOSEPH WELP, OF SAME PLACE.

VEGETABLE-CUTTER.

SPECIFICATION forming part of Letters Patent No. 633,863, dated September 26, 1899.

Application filed May 1, 1899. Serial No. 715,228. (No model.)

To all whom it may concern:

Be it known that I, JESSE M. LILLPOP, a citizen of the United States, residing at Kyana, in the county of Dubois and State of Indiana, have invented new and useful Improvements 5 in Vegetable-Cutters, of which the following is a specification.

My invention relates to improvements in vegetable-cutters; and it consists in a cutter constructed and arranged as hereinafter shown and described.

The primary object of my invention is to provide a vegetable-cutter with a reciprocating knife head or plate having a plurality 15 of diagonally-arranged upwardly-inclined knives and one or more longitudinally-arranged and vertically-extending supports for the blades intermediate their ends, the said support or supports having projecting vertical knives in rear of the cutting edge of the diagonal horizontal knives, whereby the material operated upon is cut horizontally and also vertically for dividing it into small particles.

25 In the accompanying drawings, Figure 1 is a perspective view of a machine embodying my invention. Fig. 2 is a detached perspective view of the knife-carrying plate and the knives. Fig. 3 is a vertical sectional central 30 view taken through the knife-supporting plate and transverse the horizontal knives.

Referring now to the drawings, A indicates a rectangular frame supported at its corners by the feet B. Projecting from one end of the frame or base A are the standards C, and journaled in the upper ends of these standards is a transverse shaft D. This shaft has both ends projected through the standards and one end provided with an operating crank-40 handle E and the opposite end with a balance-wheel F.

Projecting from the end of the rectangular frame below the transverse shaft is a standard G, and journaled in this standard and 45 the adjacent standard C is a short shaft H, having its inner end projecting through the standard G and provided with a crank-pin I and carrying a pinion or cog wheel J between the standards C and G. The transverse shaft

thereabove carries a cog-wheel K, which 50 meshes with the pinion or wheel J, and the cog-wheel K is preferably larger than the pinion, whereby the short shaft is revolved more rapidly than the transverse driving-shaft.

Supported at the opposite end of the base 55 or frame A is a hopper M, which extends transverse the frame and has its ends resting upon the side bars thereof. This hopper has an open lower end and is provided with a follower N for forcing the material therein in 60 contact with the cutters.

Secured to the inner sides of the side bars of the frame A are the supporting-guideways P, upon which rest the ends of a knife-carrying plate Q. This knife-carrying plate Q is 65 provided with a diagonal opening R, intermediate its ends, and situated in this opening R are a plurality of horizontal diagonally-extending and upwardly-inclined knives S, whereby a drawing cut is effected upon the 70 material being operated upon. For the purpose of supporting and holding these horizontal knives rigid at points intermediate their ends and also for the purpose of cutting the material operated upon vertically as well 75 as horizontally, and thus dividing it into small pieces, are the vertically-arranged bars a, having the angular notches b, the rear vertical walls c of the notches formed into cutting edges for producing a vertical cut upon the 80 material acted upon, and thus dividing it into small pieces. I here show two of these supports carrying the vertical knives arranged behind each of the horizontal knives; but it will be readily understood that one or as many 85 as may be desired will be provided for dividing the material into large or small pieces.

Having thus described my invention, what I claim, and desire to secure by Letters Patent, is—

1. A cutter for vegetable-cutters comprising transversely-extending upwardly-inclined horizontal knives, and a longitudinal supporting-bar situated beneath the knives and having angular notches with vertical rear cutting edges situated behind the horizontal knives, substantially as described.

2. A cutter for vegetable-cutters comprising

ing a plate having a diagonal opening, horizontal knives extending transverse said opening and inclined upwardly and longitudinal supporting-bars beneath the knives and having angular notches with vertical rear cutting edges situated behind the horizontal knives, substantially as described.

In testimony whereof I have hereunto set my hand in the presence of two subscribing witnesses.

JESSE M. LILLPOP.
